Patented July 3, 1928.

Des. 75,675

UNITED STATES PATENT OFFICE.

JAMES H. BOYE, OF CHICAGO, ILLINOIS.

DESIGN FOR A CURTAIN AND PORTIÈRE ROD.

Application filed April 18, 1928. Serial No. 26,375. Term of patent 7 years.

To all whom it may concern:

Be it known that I, JAMES H. BOYE, a citizen of the United States, residing at Chicago, in the county of Cook and State of Illinois, have invented a new, original, and ornamental Design for Curtain and Portiere Rods, of which the following is a specification, reference being had to the accompanying drawings, forming part

Fig. 2 is an enlarged cross-section of the rod.

I claim:

The ornamental design for a curtain and portière rod, as shown.

JAMES H. BOYE.
